CLAIM

The ornamental design for a serving tub, as shown and described.

DESCRIPTION

FIG. 1 is a top, front perspective view of a serving tub showing our new design.

ing our new design.
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view.
The broken lines indicate optional wood graining of the handles of the serving tub and form no part of the claimed design.

1 Claim, 7 Drawing Sheets
